UNITED STATES PATENT OFFICE.

CHESTER H. BRASELTON, OF TOLEDO, OHIO, AND FRED M. CARROLL, OF NEW YORK,
N. Y.; SAID BRASELTON ASSIGNOR TO SAID CARROLL.

PENCIL.

1,292,426.

Specification of Letters Patent. Patented Jan. 28, 1919.

Continuation of application Serial No. 695,342, filed May 6, 1912. This application filed January 30, 1917.
Serial No. 145,369.

To all whom it may concern:

Be it known that we, CHESTER H. BRASELTON and FRED M. CARROLL, citizens of the United States, residing at Toledo, in the county of Lucas and State of Ohio, and New York, in the county of New York and State of New York, respectively, have invented certain new and useful Improvements in Pencils, of which we declare the following to be a full, clear, and exact description.

This invention relates to pencils and particularly to that class of pencils in which the lead is protruded from its holder or casing as the lead is worn away keeping the pencil of substantially the same length, as distinguished from the class of pencils in which the covering for the lead usually of paper or more often wood is gradually cut away or removed to keep the lead exposed.

This is a substitute application of our earlier application Serial No. 695,342 filed May 6, 1912.

The main object of the invention is to construct a pencil of more economical manufacture than those at present on the market and of simpler and more efficient construction and operation. These objects are obtained in the present invention through the provision of novel means for protruding the lead from its casing when desired, which means includes a fluid body of liquid, semi-liquid or plastic material confined in the casing of the pencil and adapted upon application of pressure to act on the end of the lead opposite that to be used and project the latter end from the pencil casing. The means for applying pressure to the fluid material is allowed to move in one direction, namely that which tends to protrude the lead from the casing but the construction in this respect is such that the non-solid backing for the pencil can not yield in the opposite direction to allow the protruded lead to recede into its casing as the pencil is used.

Other and incidental objects will readily appear from the following description of the invention taken in connection with the accompanying drawings which accompany and form a part of this specification and in which:

Figure 1 is a longitudinal sectional view of our improved pencil.

Fig. 2 is a transverse sectional view taken

on the line 2—2 Fig. 1 looking in the direction of the arrows.

Fig. 3 is a detail, enlarged sectional view of the backing plug for the lead.

Fig. 4 is an enlarged view of a portion of the metallic lead inclosing tube, and

Fig. 5 is an end view of the tube shown in Fig. 4.

In the drawings, 1 indicates the main portion of the pencil which may be made of wood, metal or other suitable substance. 65 This is provided with a chamber 2 in one end, which is connected with the opposite pointed end 3 of the main portion 1 by a longitudinal bore 4. Inserted within the bore 4 is a metallic tube 5, the bore of which 70 is slightly restricted at the end 6, which end is split at one point 7 on its periphery to provide a yielding grip by this portion 75 of the tube on the inclosed lead. The end 6 of the metal tube is beveled as shown at 8 75 to continue the pointed effect of the pencil beyond the end of the main portion 1. A core of lead 9 is located in the tube 5 and when of its original length extends from substantially one end of this tube to slightly 80 beyond the other end sufficiently, however to be exposed enough for use. A backing plug 10 cupped at one end, as shown at 11, is located within the tube 5, with its uncupped end adjacent the unexposed end of 85 the lead core 9.

Rigidly mounted within the chamber 2 of the main portion 1 of the pencil is the enlarged head 12 of the tube 5. This head portion of the tube is provided with a cavity 90 13 which connects at 14 with the bore of the metallic tube proper. The head 12 is internally screw threaded at 15, the threads co-operating with external threads on a plug 16, closely fitting the cavity 13 of the head 12. The non-solid or plastic material is placed in the cavity 13 of the head 12 and screwing of the plug 16 into this cavity is adapted to cause the material therein to flow down the bore of the metal tube 5, pushing 100 ahead of it the backing plug 10 and the lead 9 which it engages. In this way the lead 9 may be protruded from the tube 5 as the pointed end of the pencil becomes used away in use.

To provide means for readily turning the screw threaded plug 16 when it is desired to project the lead from the point of the

pencil, the plug is provided with a head 17 having ratchet teeth 18 on one side of it coöperating with opposed ratchet teeth on a disk 20, which is loosely mounted upon a 5 reduced portion 19 of the plug which axially projects beyond the head 17 and the ratchet teeth 18. This reduced portion loosely carrying the disk 20 is surrounded by a coil spring 23 bearing at one end upon the disk 10 20 and with its other end upon an enlarged portion 22 of the reduced portion 19 of the plug. This spring serves at all times to engage the ratchet teeth 18 with the opposing ones of the disk 20 and these teeth are so 15 shaped, as shown in the drawing, that rotation of the disk 20 in a clockwise direction, Fig. 2, will similarly rotate the plug 16 so as to force a portion of the fluid material confined in the cavity 13 into the tube 5 and 20 project more of the lead from said tube at the pointed end of the pencil. In the particular form shown rotation of the disk 20 in a counterclockwise direction, Fig. 2, does not rotate the plug 16, the ratchet teeth of 25 the disk merely slipping over those of the head 17 being allowed so to do by the spring 23. In this way the lead 9 may be protruded from the tube 5 and the pointed end of the pencil as it becomes worn away in 30 use.

A sleeve 24 which serves also to cover the inclosed mechanism and to support an erasing rubber 25 for the pencil provides a means for rotating the disk 20 in either direction. This sleeve is supported by the end of the main portion 1 of the pencil and is internally beaded at 26, which beading is located in a circumferential groove in the main portion 1, thus providing such connection 40 between the sleeve and the member 1 that they may have independent rotation but no independent longitudinal movement. Diametrically spaced longitudinal ribs 21 are provided in the sleeve 24 which play in corresponding notches 27 in the periphery of the disk 20. Through these ribs and notches the rotation of the sleeve 24 is communicated to the disk 20. As above described, rotation of the disk 20 in one direction only is effective to rotate the plug 16. The erasing rubber 25 is supported in the end of the sleeve 24 in the usual manner by an internal circumferential beading 28.

While the form of construction herein shown and described is admirably adapted to fulfil the objects primarily stated, it is to be understood that it is not intended to confine the invention to the one form of embodiment herein shown and described, as it is susceptible of embodiment in various forms all coming within the scope of the claims which follow.

What is claimed is:

1. A pencil comprising the combination 65 of a casing, a lead movably mounted therein,

a fluid backing for the lead, and means for applying pressure to the fluid backing to protrude the lead from its casing.

2. In a pencil, the combination with a casing having a longitudinal opening therethrough enlarged at one end, of a lead mounted in the opening in the casing, extrusive material mounted in the enlarged portion of the opening and at the back of the lead, and means for applying pressure to 75 said material to force a part of it from the larger portion of the opening into the portion of smaller diameter and thus project the lead from its casing.

3. In a pencil, the combination with a casing having a longitudinal opening therethrough, of a lead mounted in said opening, a cavity at the back of the lead in communication with said opening, fluid material in said cavity, a plug working in said cavity, 85 and means for forcing the plug into the cavity to force a portion of the material therein from it into the opening in the casing and behind the lead whereby the latter may be protruded from the casing. 90

4. A pencil comprising a casing having a longitudinal opening, a tube mounted in the opening adapted to yieldingly hold a lead therein, fluid material at the back of the lead in the tube and in a recess at one end 95 thereof, a plug for forcing the material from the recess into the tube, and means for forcing the plug into the recess operable from the exterior of the pencil whereby the lead when desired may be protruded from 100 its casing and tube.

5. A pencil comprising the combination with a casing having an opening therethrough, of lead mounted in the opening, a recess of larger diameter than the opening 105 but in communication therewith in one end of the casing, and with its walls internally screw threaded, fluid material in the recess, a screw threaded plug working in the recess with its threads coöperating with the 110 threaded interior surface of the walls of the latter, a sleeve mounted on the adjacent end of the casing, and connections between the sleeve and the screw plug whereby rotation of the former effects rotation and 115 movement of the latter into the recess and forces some of the fluid material from the latter into the opening in the casing to protrude the lead from the pencil.

6. A pencil comprising the combination 120 of a casing, a longitudinal bore therein, a recess in one end of the casing of larger diameter than the bore and internally screw threaded, a lead mounted in the longitudinal opening of the casing, extrusive material 125 mounted in the recess in the end of the casing, an externally screw threaded plug working in the recess in the casing and having a headed portion provided with ratchet teeth, a disk having opposing ratchet teeth 130

spring held with its teeth in engagement with the ratchet teeth on the head of the plug to rotate the latter when the disk is rotated in one direction only, and a sleeve 5 rotatively mounted upon the casing and connected with said disk to rotate the latter in either direction.

7. In a pencil, the combination of a casing; a lead mounted therein; a member moving longitudinally of the casing; and means 10 differentially transmitting the movement of said member to said lead.

8. In a pencil, the combination of a casing; a lead mounted therein; a member moving 15 longitudinally of the casing; and means transmitting the movement of said member to said lead, said motion transmitting means being adapted to multiply such movement.

9. A pencil comprising a casing having a 20 longitudinal bore, a lead mounted in the bore and adapted to be projected from one end of the casing, a chamber at the other end of the casing connecting with the bore in

the latter but of a different diameter than said bore, extrusive material mounted in 25 said chamber, and a rotary member mounted on said casing adapted when rotated to have a slight longitudinal movement relative thereto, said member co-operating with the extrusive material in the chamber to force 30 some of it therefrom into the bore of the casing and to project the lead therein from the latter, this movement of the lead being greater than the longitudinal movement of the rotary member. 35

10. In a pencil, the combination of a casing, a lead mounted therein, a longitudinally movable member for protruding the lead therefrom, and capable of rotative movement, and ratchet connection for rotating said member and through said rotation moving said member longitudinally. 40

In witness whereof we have hereunto set our hands.

CHESTER H. BRASELTON.
FRED M. CARROLL.
